Patented Feb. 5, 1974

230,305

CIGARETTE LIGHTER

Samuel J. Koch, % Korex Industries, 821 Malcolm
Road, Burlingame, Calif. 94010

Continuation-in-part of design application Ser. No.
211,838, Dec. 23, 1971. This application Nov. 9,
1972, Ser. No. 304,958

Term of patent 14 years

Int. Cl. D27—05

U.S. Cl. D48—27 R

FIG. 1

FIG. 2

FIG. 3

FIG. 1 is an exploded top perspective view of a cigarette lighter showing my new design, the opposite side being a mirror image of the side shown;

FIG. 2 is a rear elevational view thereof on a reduced scale; and

FIG. 3 is a bottom plan view thereof on a reduced scale.

This is a continuation-in-part of design application Ser. No. 211,838, filed Dec. 23, 1971.

I claim:

The ornamental design for a cigarette lighter, as shown and described.
